UNITED STATES PATENT OFFICE.

HOWARD W. SOFER, OF DETROIT, MICHIGAN.

VENTILATED FIREPROOF STOVE-INCLOSURE UNIT.

Application filed September 8, 1924. Serial No. 736,482.

This invention relates to a structure which is adapted to be placed as a unit, within a building, to provide an extension for a room thereof and which extension or compartment 5 is arranged to serve as a kitchen for containing a cooking stove and other necessary cooking utensils and materials.

An object of the invention is to provide a kitchen unit which may be readily set within 10 an opening in the wall of a building and arranged to close said opening, and provided with a closure for closing the opening into the unit whereby the compartment formed by the unit may be shut off from the room of the 15 building into which it opens and is concealed from view. A further object is to provide a fire proof unitary structure for housing a stove and which unit may be tightly closed to protect the building against loss by fire 20 caused by the use of the stove, and within which unit cooking may be done without the occupants of the house being annoyed by odors.

A further object is to provide an arrangement whereby a draft is created through the 25 unit to draw off fumes, smoke and odors, and to ventilate the room into which the device opens. It is also an object to provide a unit structure which is made up of detachable 30 parts or sections and which may be cheaply constructed and installed, the construction being such as to facilitate installation and lessen the cost of transportation and handling, and which unit when installed will present 35 the appearance of a built-in part of the building and will have the appearance also of a cupboard or cabinet with the doors flush with the room wall.

A further object is to provide a unitary 40 structure for the purpose which may be detachably set within an opening in the wall and forms a tight closure for said opening and the construction of which unit is such as to effectually exclude the exterior cold or heat 45 and is made up of detachable sections which when set up are so fitted together as to effectually exclude the elements and a knock-down structure is provided which may be 50 cheaply transported to and assembled at the place of installation.

A further object is to provide a structure of the character described which may be conveniently placed within an opening in the outside wall of the building to project beyond 55 said wall and the construction of which structure is such as to provide an insulating air

space within the walls of the structure, and the roof portion is also provided with an air space and with a ventilating canopy and flue.

With the above and other ends in view the 60 invention consists in the matters hereinafter set forth and more particularly pointed out in the appended claims reference being had to the accompanying drawings in which

Figure 1 is a perspective view of a kitchen 65 unit illustrative of the invention and set up ready for installation;

Fig. 2 is a perspective view of the several 70 detachable sections of the unit and showing these sections separated to more clearly disclose their construction and manner of assembly;

Fig. 3 is a transverse vertical section 75 through the unit with portions broken away to shorten the figure;

Fig. 4 is a horizontal section of the same 80 with portions broken away to reduce the figure in width;

Figs. 5, 6, 7 and 8 are perspective details 85 showing interlocking edge portions of bottom and side walls of the structure; and

Fig. 9 is a front elevation of the unit showing doors for closing the front of the same, in open position and a stove in place within the compartment formed by the unit. 85

The structure comprising the unit embodying the present invention consists of a top or roof section 1, a back wall section 2, side wall sections 3 to the forward edges of which doors 4 are connected by hinges 5, and a bottom or 90 floor section 6. The back wall 2 and side walls 3 are preferably formed hollow and of inner and outer sheet metal plates 7 and 8 respectively, which are spaced apart by wood strips 9 extending along the edges of the 95 plates and forming a spacing frame to space apart the sheet metal plates forming the wall. In a like manner the back wall or section 2 is formed of inner and outer sheet metal plates 10 and 11 which are spaced apart by a like 100 wood frame 9 and the bottom or floor section 6 comprises a wood floor 12 which is covered by an inner sheet metal covering 13 and an outer like covering 14. The meeting edges of the back and side walls and of the floor section 105 and these walls, are all formed to interlock in such a manner that they may be readily assembled or disassembled, and will provide air tight and water proof joints. To provide such an interlocking edge portion for 110 the back wall 2, the side edges are provided with a channel strip 15 formed of sheet metal

with the free edges of the metal folded backwardly of the side flanges of the channel and spaced therefrom to provide a groove 16 for the purpose of receiving the edges of the metal sheets 10 and 11. This channel also extends across the upper edge of the back wall to form an edge portion for engagement with the roof section 1 of the structure.

The side wall sections 3 are formed at their rear edges with a channel to receive the edge channel 15 of the rear wall and this channel formed on the side walls is constructed by bending the edge portion of the metal plate 7 of each wall against the outer side edge of the frame 9, thence outwardly longitudinally of the wall, and thence inwardly, forming a channel 19 to receive and embrace the edge channel 15 of the back wall. The edge portion of the outer plate 8 of each side wall is extended past the frame 9 and in contact with the longitudinally extending portion or bottom of the channel formed by the inner plate 7, and then is bent at right angles to engage the outer side of the outer flange 17 of the channel and then bent over the edge of this flange and formed inwardly against the inner side thereof, forming a loop portion 18 to embrace and strengthen the outer flange 17 of the channel 19 within which the edge of the back section is adapted to fit closely. When these edges are so assembled, they may be secured together detachably by means of screws 20 (Fig. 4) passing through the outer flange of the channel, through the edge portion of the back wall, and into the wood filler 9 of the side wall. These screws tend to bend the outer flange 17 of the channel inwardly against the back wall and thus a very tight joint is secured and the parts are firmly held together. The channel strip 15 reinforces and stiffens the edge of the back wall to obviate liability of damage to the parts during transportation, and the channel formation on the side walls, the outer flange of which is reinforced by the overturned portion 18, also forms a strengthening and stiffening member for the edges of the side walls or sections.

The forward edges of the side wall sections are each formed by bending the edge portion of the metal plate 8 around and against the forward edge of the filler 9 and thence inwardly as at 21 against the inner face of the filler, as shown in Fig. 4, thus securely fastening the forward edge of said plate to said filler, and the forward edge portion of the plate 7 is formed across and upon the inturned edge portion of the plate 8 which lies against the filler and is extended for a distance beyond the outer surface of the plate 8 and folded backwardly upon this extended portion to form a laterally outstanding flange 22 of double thickness of metal, the free edge portion 23 of the metal being formed down upon the outer surface of the plate 8 and secured thereto in any suitable manner. The

plates 7 and 8 are thus firmly held in place upon the filler strip 9 and the forward edge of this strip is protected and the forward edge of the wall is strengthened and stiffened by this folding over of the two edge portions of the two plates of the wall. The plate 7 is also formed with the laterally outstanding flange 22 which is adapted to overlap and lie upon the inner surface of the wall of the building within an opening in which the unit is inserted, and thus the crack or opening between the unit and the edge of the wall opening of the building is completely closed when the unit is in place, to provide a tight joint and to assist in holding the unit in place within the opening in the wall.

The doors 4 are attached to the forward edges of the side wall sections by means of the hinges 5 with these doors lying flat against the edge face of the side walls formed by the folded over edge portion of the plate 7. One leaf of each of the hinges 5 is passed through an opening in the flange 22 and the leaf is secured in any suitable manner to the side wall by screws or other fastening means passing through the leaf and into the filler strip 9 with the leaf lying flat against the outer side of the side wall section.

The doors 4 are also preferably made of sheet metal plates 24 and 25 with the edge portions of the plate 25 folded over the edge portions of the plate 24 to stiffen the edges of the doors, and panels are provided in each door by spacing the central portion of the outer plate from the inner plate, thus providing an air space between the plates for the purpose of preventing warping and to insulate the door against high heat within the kitchen unit. These walls are spaced apart by means of a filler frame 26 which also forms a frame around a window 27 in the door and adjacent the floor unit 6 near the lower edge of each door, a series of openings 28 is provided for admitting air from the room of the building into the compartment or interior of the kitchen unit when the doors are tightly closed.

The lower edge of each side wall section 3 is formed to interlock with the side edges of the floor section 6 and a like edge formation is provided upon the lower edge of the back wall section and the back edge of the floor section for the same purpose. The side and back walls are formed with an outer downwardly extending reinforced flange 29 and also with an inner parallel downwardly extending flange 30, and the side and back edges of the floor section are formed with an upwardly extending reinforced flange 31 to engage between the flanges 29 and 30 on the side and back walls. The flange 31 is formed by bending the edge portion of the sheet metal 13 downwardly against the outer edge of the floor board 12, thence outwardly and then upwardly providing a channel 32 the outer flange of which

forms a part of the flange 31, and the plate 14 is carried beyond the edge of the floor 12 thence bent upwardly against the outer face of the side flange of the channel 32, thence over the 5 edge of said flange and downwardly against the inner surface thereof, to reinforce said flange and to stiffen the edge portion of the floor section. The flange 9 is formed by bending the edge portion of the plate 7 outwardly 10 against the lower edge of the filler 9, and thence downwardly with its outer face in the plane of the outer face of the filler and the plate 8 is extended downwardly in contact with this outer face and folded over the downwardly extending portion and over one side 15 flange of a channel member 33 which lies in contact with the lower edge of the wall section. The flange 29 is thus formed of four thicknesses of metal with the edge portions 20 of the plates 7 and 8 firmly secured together by the folded over edge portion of the plate 8. A very rigid outer flange 29 is thus formed to engage the outer side of the flange 31 on the floor section and to strengthen and stiffen the 25 lower edges of the side wall and back wall sections. The inner flange of the channel member 33 is folded backwardly upon itself to give double strength and thickness to the flange 30 which is adapted to be engaged and 30 fit within the channel 32, thus forming a tight joint between the bottom, side and back wall sections, which may be detachably secured together in any suitable manner.

The roof or top section 1 of the unit comprises a box-like structure formed of a single thickness of sheet metal with a front side or panel 34 and back wall 35 and end walls 36. The top wall 37 of this section forms the roof of the unit and may be inclined downwardly 40 toward the back wall 35 so that when the unit is placed within an outer wall of a building, the water will drain off. The front panel 34 and ends 36 are interlocked with the edges of the roof 37 by folding the edge portion of 45 the metal of these walls over an upturned edge portion of the roof plate, thus forming an upstanding flange 38 (Fig. 3) across the front and along the ends of the roof, the flange across the front being adapted to engage the inner surface of the wall of the building when the unit is inserted in an opening in such a wall, to close the crack, and make a tight joint, and this flange 38 at the ends of 50 the unit prevents the water from flowing over said ends and running down upon the outer surface of the end walls of the unit. At the outer rear end of the unit, the roof 37 is interlocked with the wall 35 by bending the edge portion of the roof metal over an outturned 55 portion of the plate 35, thus forming an outstanding flange 39 which serves the purpose of eaves for the structure to shed the water therefrom at the outer rear end of the unit.

A channel 40 is formed along rear edge 60 and end walls of the lower side and back wall,

units 2 and 3, thus providing a firm seat for the top or roof section and also interlocking this section with the upper edges of the walls of the structure. The upper or roof section is not only held firmly in place by this interlocking arrangement but assists in holding the upper edges of the side and back walls. A canopy 41 of conical shape is provided 70 within the interior of the box-like structure of the roof section, with the lower edges of 75 this conical canopy or hood secured to the lower edges of the top section and with its side walls converging toward a flue or pipe 42 which extends out through the roof 37 and is provided with a suitable damper 43 for 80 regulating the draft through this flue from the interior of the kitchen unit. This canopy 41 forms an upwardly tapering top wall 85 for the chamber or interior of the kitchen unit so that the draft created by the flue 42 will draw off smoke, odors or fumes from the interior of the structure and will also draw odors from the room of the building into which the unit opens and provide ventilation 90 therefor.

A unit structure is thus provided which may be readily placed within an opening in the wall of a room of a building to provide an extension for this room within which a stove of any type suitable for cooking may be 95 placed, access to the unit being gained by the opening of doors which form the front wall of the unit and close the opening in the wall of the building. The compartment formed by the unit may thus be closed up at any time and 100 all that will be seen from the interior of the room of the building will be the front end of the unit which will have the appearance of a cabinet set into the wall and may be made very attractive by a proper panelling 105 of the doors and of the front panel 34 within which may be mounted as shown in Figs. 1, 3 and 9, a clock 44 and suitable switches 45 and 46 for electrical connections.

As this entire unit is made up of separable 110 sections detachably interlocked, the structure may be readily installed and may be shipped in the knock-down. The structure is also such that it forms a fire proof unit particularly adapted to house a stove, the doors 4 may be closed and the fire confined so that no harm 115 will be done. The unit is particularly adapted for installation in an opening in the outer wall of a building but may with equal facility and usefulness be installed within an opening in an inside wall or within a space provided therefor in constructing a building, and the ventilating flue 42 connected with a suitable flue of the building.

Changes may be made in the particular 125 construction and arrangement of parts, within the scope of the appended claims without departing from the spirit of the invention and I do not therefore limit myself to the particular construction shown.

What I claim is:—

1. A knock-down sectional unit adapted to be placed within an opening in a wall of a building to form a fire-proof extension for a room of the building, said unit comprising top and floor sections and end and back wall sections, all of said sections being formed substantially fire-proof with interengaging edge portions, said floor section forming an extension of the floor of the room, said top section including a canopy with a flue leading from said canopy and a front wall to fill the upper part of the opening in the room wall, and a movable closure for the front side of said unit, said closure being of a vertical length substantially equal to the vertical length of said end and back wall sections and extending from the room floor to the lower edge of said front wall of the top section and from one end wall section to the other to expose the entire interior of the unit between said end sections, top and floor sections.

2. A knock-down sectional unit adapted to be placed within an opening in a wall of a building to form a fire-proof extension for a room of the building, said unit comprising top and bottom sections and end and back wall sections, said top section being a box-like structure and including a canopy housed therein with a flue leading from said canopy through the top of the section, certain of said sections being formed of sheet metal plates spaced apart to provide hollow walls for the sections and certain of said sections being formed with grooves along their edges to receive edge portions of adjacent sections and with front edge flanges to overlie and close the space between the wall openings and said unit, means for detachably securing said sections together along their interlocking edge portions, and a sheet metal closure for the front of said unit attached to certain of said sections adjacent said flanges to close the front of the unit substantially flush with the inner surface of the room wall, said closure having dimensions substantially equal to the vertical length of the end and back wall sections and being movable to expose the interior of the unit between the canopy and the bottom section.

3. A fire-proof unit for placement within an opening in a wall of a building to form an extension for a room of the building, said unit having hollow vertical walls and a box-like top section providing a roof and an upward extension of said walls, a conical canopy within said top section connected at its lower end to the bottom edge portion of said top section, and a flue leading from the apex of said canopy and extending through the roof of said top section, said top section providing an air space between said canopy and roof.

4. A knock-down sectional fire-proof unit for insertion in an opening in a wall of a building to form an extension of a room of

the building, said unit including vertical hollow sheet metal end and back walls detachably connected along their meeting edge portions and a box-like top section providing upward extensions of said walls and a roof, and including a canopy enclosed therein forming the top of the space within the unit and a flue connected to the canopy and extending through the roof, and a fire-proof door extending from said top section to the room floor and hinge-connected to one of said end walls for closing the front side of the unit which opens into the room of the building and which door when closed is substantially flush with the inner surface of the room wall, said door being provided with an opening near its lower end adjacent the floor to admit air from the room of the building to the interior of the unit when the door is closed.

5. A fire-proof unit for insertion in an opening in a wall of a building including hollow end and back walls formed of spaced apart sheet metal plates with said walls formed with interlocking edge portions, a boxlike top section forming a roof and providing extensions of the walls of the unit and provided with an internal canopy secured thereto and forming the entire ceiling of the interior of said unit with a space between said roof and canopy of said section, a flue connected to said canopy and extending through said roof, a floor section for said unit including inner and outer sheet metal plates and a wood filler between said plates, said floor section extending substantially in the horizontal plane of the room floor of the building to form a continuation thereof, means for detachably securing the top and floor sections to the wall sections, and a fire-proof door extending from the lower end of the top section to the floor section and forming a closure for the opening of the unit into the room of the building, said door being hinge-connected to the forward edge portion of one of the end wall sections and provided with an opening near its lower end to admit air to the unit.

6. A knock-down fire-proof unit for insertion in an opening in a wall of a building to form an extension for a room of the building, said unit comprising a top section, end and back wall sections and a floor section, said wall sections each comprising a frame and inner and outer sheet metal covering with edge portions of said sheet metal covering folded over said frame and interlocked to secure the same to said frame and said edge portions being also folded to form a groove along the edge of the unit and a flange forming one side of said groove, certain of said wall sections being provided with a channel member along an edge of the section with said edge portions of said sheet metal interlocked with said channel member, and said top section comprising a roof and depending walls and an

interior conical canopy with the lower edge portions of said canopy secured to the lower portions of said walls and its upper end opening into a flue extending through the roof; 5 means for detachably securing the lower edge portions of the depending walls of said top section in interlocked engagement with said end and back wall sections; means for securing the lower ends of said end and back wall 10 sections in interlocked engagement with said

floor section; and fire-proof doors hinge-connected to the forward edges of said end wall sections to close the opening from the interior of said unit into the room of the building, said doors being provided adjacent the floor section with openings to admit air to the interior of the unit when said doors are closed. 15

In testimony whereof I affix my signature.

HOWARD W. SOPER.
